GUN MOUNTING WITH PERISCOPIC ARTICULATED GUN SIGHT

Wolfgang B. Klemperer, Los Angeles, and George Tharratt, Santa Monica, Calif., assignors to Douglas Aircraft Company, Inc., Santa Monica, Calif., a corporation of Delaware

Application September 16, 1939, Serial No. 295,288

7 Claims. (Cl. 89—37.5)

Our invention relates in general to armament and especially to armament for aircraft, and relates in particular to a gun and gun sight having a number of novel features as hereinafter set forth.

It is an object of the invention to provide in a gun emplacement especially suited for use on aircraft a gun pivotally mounted for purpose of aiming, and a gun sight associated with the gun which will enable the gunner to occupy a position other than one in which his line of vision is aligned with the axis of a sighting means secured to and moving with the gun. For example, in the ordinary sighting of rapid fire or machine guns such as used on aircraft, the gunner occupies a position with his head near the butt of the gun so that he can peer along a gun sight or telescope mounted substantially parallel to the barrel of the gun. As the gun is moved from one position to another in aiming the same, the gunner must move his head and likewise portions of his body so as to keep the optical axis of his eye or eyes in alignment with the sight. The foregoing condition has placed restrictions on the practices of gun mounting and operation, which it is an object of the present invention to avoid. In the present invention the eye of the gunner may be offset or remote from a gun sight axis disposed parallel to the gun barrel, thereby making it possible to improve the art of aircraft gunnery with respect to greater freedom in design especially with regard to the selection of positions for gun emplacement, reduction in the size of gun turrets or canopies to a minimum by reason of the fact that in the practice of the invention it is not necessary for the gunner to occupy the gun turret, the mounting of guns exteriorly of sealed cabins in which the gunners reside in an oxygen supplied atmosphere or one maintained at higher pressure than the pressure of air external to the cabin, and greater ease and rapidity of gun pointing by reason of the fact that the gunner need move but little from a normal position in a gunner's seat, or not at all, while the gun is moved rapidly through selected arcs of movement from one aiming position to another.

It is an object of the invention to provide with a gun which is movably mounted for the purpose of aiming, a gun sight having a view piece containing an objective lens system, which view piece is connected to the gun so as to move therewith so as to maintain the optical field of the gun sight in a prescribed relation to the line of travel of a projectile fired from the gun, a gun sight

eyepiece disposed in a position convenient to the sight of a gunner, and an articulated connection between the view piece and the eyepiece providing relative movement of the view piece and the eyepiece and having optical means for transmitting the image received by the objective lens system of the view piece to the lens system of the eye piece.

It is a further object of the invention to provide with a gun mounted so as to have movement relative to two intersecting substantially perpendicular axes, a gun sight having a field lens system embraced in a view piece connected to the gun so as to move therewith relative to both axes, an eye lens system carried in an eyepiece mounted so as to move only on one of the axes, and an articulated lens system for transmitting to the eye lens system the target image received by the field lens system.

20 Referring to the drawings which are for illustrative purpose only:

Fig. 1 is a fragmentary section showing preferred forms of our invention.

Fig. 2 is an enlarged fragmentary section taken substantially as indicated by the line 2—2 of Fig. 1.

Fig. 3 is a cross-section taken substantially as indicated by the line 3—3 of Fig. 2.

Fig. 4 is an enlarged fragmentary sectional view taken as indicated by the line 4—4 of Fig. 3.

Fig. 5 is a diagram of the optical system employed in our invention.

Fig. 6 is an enlarged fragmentary cross-section through the desiccator.

35 In Fig. 1 we show a wall 10 forming a chamber 11 which may be isolated from the external atmosphere. Such wall 10 may be a part of the body structure on the aircraft and the chamber 11 may be substantially sealed so that a desired atmospheric condition may be maintained therein.

40 A turret 12 is shown projecting externally from the wall 10, such turret being of relatively small size and having a minimum projection from the wall 10 considering the size of gun and operating mechanism employed therefor. The turret 12 is substantially spherical and the lower portion 13 thereof occupies a hemispherical depression 14 in the wall 10. A gun 15 is mounted in the turret so as to project therefrom and a

45 gunner's support preferably in the form of a seat 16 is provided within the chamber 11 preferably directly below the turret 12, there being a perisopic gun sight 17 having an eyepiece 18 disposed convenient to the optic of a gunner 19 occupying the seat 16. The perisopic telescope

gun sight 17 provides a means whereby the gunner within the chamber 11 may have external vision and may readily sight the gun 15 on a target. Under his control means are provided as will be later explained whereby the gun may be rapidly swung with universal movement so as to be brought quickly to bear on a target.

In the present arrangement the gunner does not occupy a space within the rotating turret and accordingly the size of the turret may be reduced so as to accommodate only the butt end of the gun and the associated operating mechanism. Therefore, the projection of the armament from the wall 10 may be maintained substantially at a minimum so that the drag on the aircraft due to the projection of the armament need not be large. As shown in Figs. 2 and 3, the wall forming the depression 14 supports an annular track 21 around its upper edge and a central bearing structure 22 in the bottom thereof and defining a vertical axis of rotation A—A. Through this bearing structure 22 a hollow column or hollow supporting arm 23 is coaxially extended. This column 23 being connected at 24 to a central bearing structure 25, which, as shown in Fig. 4, carries roller bearings 26 for supporting a gun mount including two portions joined together by bolted flanges 27, these two portions comprising a gun support 28 and a drive section 29, these parts 28 and 29 being disposed on opposite sides of the bearing structure 25 and having tubular shafts 30 and 31 projecting therefrom on the lateral axis of rotation B—B coaxial with the bearings 26, the outer ends 32 of the shafts 30 and 31 being carried by bearings 33 mounted on a ring 34 which is supported in the track 21.

The drive section 29 is hollow and has a passage 35 coaxial with the interior space 36 of the bearing structure 25. The drive section 29 has a housing 37 projecting upwardly and forwardly, as shown in Fig. 3, this housing having a passage 38 which joins the passage 35 in the manner of an elbow. The drive section carries a worm wheel segment 39, Figs. 3 and 4, in downwardly projecting relation so as to be engaged by a worm screw 40 carried in a housing 41 fixed at the upper end of the column 23. The worm is selectively driven by a suitable power means, here represented as a motor 42 whereby the gear segment may be caused to rotate through a limited arc around the axis B—B, to swing the gun mount in such a manner that the gun 15 will be elevated or depressed. As best shown in Fig. 2, the central bearing structure 22 comprises a packing box 43 for sealing around the column or rotatable arm 23 where it projects from the interior of the cabin 11 through the wall 20. A worm gear 44 is secured rigidly to the upper end of the outer wall 22' of the packing box so that it will be held stationary around the column 23. A housing 45 is secured to the column in a position to cover the stationary worm gear 44, and supports therein a worm screw 46 for engagement with the worm gear 44, there being a ball type thrust bearing 47 mounted on the upper face of the worm gear so as to engage the radial wall of the housing 45 to support the load of the column 23 and a major portion of the vertical load of the gun mount situated at the upper end of the column 23. A motor 48 is mounted by means of a bracket 49 on the housing 45, and this motor is connected to the screw 46 so as to drive the same and to thereby accomplish rotation of the turret 12 and the cooperating gun and mounting parts on the axis A—A. By coopera-

tive use of the motors 42 and 48 the gun 15 may be swung relative to the axis A—A and B—B whereby it may have universal movement enabling it to be aimed readily at a target within a given range.

The invention also includes novel features and constructions embraced in the gun sight 17 which comprises an articulated telescope with a view piece 50 supported so that it will be always in a prescribed position relative to the gun 15. For example, in the present invention the optical axis of the view piece 50 is disposed substantially parallel to the barrel 51 of the gun 15.

In the preferred practice of the invention I have used parts of the gun mount and column structure to form the articulated gun sight. For example, I prefer to mount the diagonal supporting tube 52 on the tubular housing 37, this tube 52 having a housing 53 at its upper end by which it is connected to the view piece 50. Within this housing 53 a suitable image reflecting means, such as a prism 54 is mounted, so that the image received by the lens system of the view piece will be reflected down through the tubular arm 52. Here the image passes through a dove prism 55 secured in a sleeve 56 which is rotatable in the lower portion of the tube 52. A reflecting means 57, in the form of a mirror or prism, is mounted in the elbow formed by the intersection of the passages 38 and 35, the image being thereby reflected to another diagonally disposed reflector 58 positioned in the space 36 of the bearing structure 25 in alignment with the upper end of the column 23. In the upper part of the column 23 I place an erecting lens system comprising lenses 60 and 61, and at the lower end of the column 23 there is a housing 59 carrying a diagonal reflector comprising a pentaprism 60 for transmitting the image to the lens system of the eyepiece 18.

The gun sight has sections which have relative rotation on the axis B—B. For example, as the gun 15 is swung upward from its position of Fig. 3, the tube 52 will revolve in clockwise direction, since such tube is connected directly to the gun mount. Accordingly, the prism 57 will have rotation relative to the prism 58, which would produce a rotation of the image at the eye piece were it not for the presence of the dove prism 55 having means for rotating it in a manner to keep the image at all times erect as the upper part of the gun sight comprising the view piece 50 and the tubular arm 52 are swung relative to the lower part comprising the column 23 and the eyepiece 18. The means for rotating the dove prism 55 includes a ring bevel gear 61 secured to the lower end of a tube 56, a bevel pinion 62 secured to the inner end of a shaft 63 which projects through the housing 37 and has a gear 64 fixed on the outer end thereof. A gear segment 65 is secured in a position coaxial with the axis B—B to a bearing case 66 which is carried on an extension or bracket 67 projecting laterally from the lower part of the bearing structure 25. The gear ratio from the segment 65 through the gears 64 and 62 to the gear 61 is one to two so that as the arm 52 and the prism 57 at the lower end thereof are rotated, there will be a rotation of the dove prism through such corresponding arc as to compensate for the image rotation which would be otherwise present.

The gunner's seat 10 is mounted on a suitable bearing plate 62a and is connected with the gun mount so as to rotate therewith on the axis A—A. This connection is accomplished by use

of a tube 63a which projects down from the column 23 to the bracket 64a on which the seat is mounted. The gunner 19 when occupying the seat 16 is positioned so that his eyes will be aligned with the eyepiece 18 so that he may readily peer into the articulated gun sight and view the external area toward which the gun 15 is pointed. By manual operation of a suitable control 65' the gunner may cause aiming movement of the gun and its cooperative view piece 50 in which the target is visible, and when the image of the target is centralized with respect to the view piece 50, the gun 15 may be fired. In Fig. 3, we diagrammatically show a control system for the motors 42 and 48 which may be operated by the gunner and which is representative of control means now known to the art. From a generator 66', a feed conductor 67' is extended to both of the motors, and from these motors conductors 68 and 69 are carried back to rheostat switches 70 and 71 which are connected through a conductor 72 with the side of the generator 66 opposite from that to which the conductor 67' is connected. These rheostat controls 70 and 71 are provided with handles 73 and 74 respectively by which they may be manually operated to control the energization with the movements required to aim the gun 15.

The lens system of the articulated gun sight is shown diagrammatically in Fig. 5. The view piece 50 has objective lenses 82 and 83 which project the image of the field to a focal plane 84 which is provided with a suitable reticule represented by the center dot 85. The image then passes respectively through the prism 54, the dove prism 55, the prisms 57 and 58, the erecting lens system comprised of lenses 80 and 81, and the pentaprism 60 to the focal plane 86, from which focal plane 86 the lenses 87 and 88 of the eyepiece carry the image to the eye of the gunner. The lenses or reflecting mediums are diagrammatically shown. For example, the orientation of the dove prism 55 on its longitudinal axis will, of course, depend upon the angle of the tube 52 relative to vertical.

A special feature of the invention consists in the provision of the telescopic gun sight with a desiccator 90 which keeps the air within the structure of the gun sight essentially dry, but permits an inflow and outflow of air as may be required to balance the interior pressure with the pressure of the external atmosphere which varies with the change in elevation of the aircraft. As shown in Fig. 6, this desiccator 90 is secured to a hollow part of the gun sight 17, for example, to the column 23 and has a fitting 91 including a cup 92 communicating through an opening 93 in its base and an opening 94 in the column 23, with the interior of the column 23. A cylindrical receptacle 95 having an open inner end 96 is connected detachably to the cup 92 as by means of a threaded joint 97. Near the lower or outer end of this receptacle 95 there is a wall 98 having an intake valve opening 99 and an outlet valve opening 100, both of these openings 99 and 100 being covered by closure discs 101 and 102 supported by springs 103. A perforate supporting wall 104 is spaced from the end wall 98 and a removable and replaceable cartridge 105 is positioned adjacent the wall 104, such cartridge including a mass of water absorbing material such as activated alumina, silica gel, etc. Adjacent the upper or inner end of the cartridge 105 there is a layer of fibrous material to filter out fine particles which may be carried toward the 75

interior of the cup 92 by the inwardly flowing air. To hold the filter 107 and the cartridge 105 in proper position for operation a removable perforate plate 108 is pressed downward by means of a spring 109 disposed within the cup 92.

As the aircraft carrying the gun sight ascends the reduction in atmospheric pressure will cause a flow of air from the interior of the gun sight 17 out through the cartridge 105 and the outlet valve 100. And likewise, when the aircraft descends the increase of the external air pressure will result in a breathing of air in through the intake valve opening 99, and the mass of material 106 of the cartridge 105 through the passages 93 and 94 to the interior of the column 23 which is connected with the remaining spaces in the gun sight. The spring pressed closure elements 101 and 102 keep the charge of the cartridge 105 isolated from the moisture of the external atmosphere, excepting such of the external air as may enter the desiccator 90 in the normal breathing of air into the interior spaces of the gun sight. Due to the changes in elevation at which the aircraft carrying the gun sight is operated, there is not only a change in applied atmospheric pressure, but also reductions in temperature which cause condensation of moisture present in isolated bodies of air. In our present gun sight reduction of temperature of air contained in the interior spaces of the gun sight will not cause fogging of the interior lenses and prism or reflector surfaces by moisture condensation, since the air which enters the gun sight is dried by the desiccator to such extent that it has a very low dew point. The active element of the desiccator 90, namely, the cartridge 105, may be replaced from time to time, and it is preferable to mount the desiccator 90 in such position that it will be easy of access. As shown in Figs. 2 and 3 a desiccator 90', of the same construction as the desiccator 90, is placed in communication with the outer part of the housing of the gun sight. It may be conveniently connected to the tubular member 52, so that it will serve the outer portion of the gun sight, whereas, the desiccator 90 will serve the inner portion of the gun sight.

In Fig. 1, in order to indicate the breadth of application to which the invention is applicable, we show a turret 12' mounted in the lower wall 10' of the aircraft body in a position to project downward therefrom, or in a direction opposite to the projection of the turret 12. By means of such turret 12' a gun 15' is mounted in a position below the body of the aircraft, and is supported by cooperating parts substantially the same as those disclosed in Figs. 2, 3, and 4, which parts are turned upside down so that the column 23' which is representative of the column 23 of the preferred form of the invention will project upward across the front of a gunner's seat 16', to support an eyepiece 18' at the upper end of the tube or column 23' in alignment with the axis thereof. A gunner 19' occupying the seat 16' may readily lean over, as shown, so as to peer down into the eyepiece 18' of the gun sight 17' associated with the gun 15', and over which the column 23' forms a part.

We claim as our invention:

1. In a gunnery device of the character described for use with a wall of a substantially sealed cabin or the like, the combination of: a hollow supporting arm; bearing means supporting said arm so that it may project through said

wall and rotate on an axis extending therewith through said wall; sealing means to seal around said arm where it passes through said wall; a gun pivotally mounted on the outer portion of said arm so as to swing on an axis extending crosswise of the axis of said arm; an articulated gun sight having a view piece connected to said gun so as to swing therewith as the gun is aimed, an eyepiece disposed within said cabin, and optical means extending in part through said hollow arm from said eyepiece to said view piece to transmit to said eyepiece the image received by said view piece; a gunner's support rotatably mounted in said cabin; and means for rotating said gunner's support with said arm.

2. In a gunnery device of the character described for use with a wall of a substantially sealed cabin or the like, the combination of: a hollow supporting arm; bearing means supporting said arm so that it may project through said wall and rotate on an axis extending therewith through said wall; sealing means to seal around said arm where it passes through said wall; a gun pivotally mounted on the outer portion of said arm so as to swing on an axis extending crosswise of the axis of said arm; an articulated gun sight having a view piece connected to said gun so as to swing therewith as the gun is aimed, an eyepiece disposed within said cabin, and optical means extending in part through said hollow arm from said eyepiece to said view piece to transmit to said eyepiece the image received by said view piece; a gunner's support rotatably mounted in said cabin so as to carry a gunner in a position to use said eyepiece; and means connecting said gunner's support to said arm so that it will revolve with said arm on the axis of said arm.

3. In a gunnery device of the character described for use with a wall, of a cabin or the like, having a depression therein, the combination of: turret means seated in said depression; a supporting arm projecting inward from said turret means; bearing means supporting said arm in a position projecting through said wall and rotating on an axis extending therewith through said wall; a gun supported in said turret means so as to swing on a line in crossing relation to said axis; an articulated gun sight having a view piece connected to said gun so as to swing with the gun in all of its directions of movement as the gun is aimed, an eyepiece disposed within said cabin, and articulated optical means extending in part along said arm from said eyepiece to said view piece to transmit to said eyepiece the image received by said view piece; and means to seal around said arm where it passes through said wall.

4. In a gunnery device of the character described for use with a wall, the combination of: an upright column member mounted so as to extend through said wall and rotate on an axis extending substantially longitudinally thereof; a gun pivotally connected to the upper end of said

column so as to rotate on an axis extending in crosswise relation to said first named axis; a gun turret mounted on the upper end of said column in a position to enclose at least a part of said gun; power means in said turret for moving said gun; a gunner's support connected to the lower end of said column so as to rotate therewith; means to seal around said column where it passes through said wall; means operative to control the operation of said power means; and a telescopic gun sight extending upward from a position contiguous to said gunner's support upward through said sealing means to a point in cooperative relation to said gun.

5. In combination with a gunnery device of the character described having an aimable gun, a gun mount pivotally supporting said gun and means to pivotally support said gun mount, power means operative to move said gun for the purpose of aiming the same, and control means for said power means operative by a gunner: a gunner's seat connected to said gun mount so as to move therewith as the gun mount is swung on said means to pivotally support the same; a gun sight having a view piece, an eye piece, and articulated optical means for transmitting to said eye piece the image received by said view piece; means for connecting said view piece in fixed relation to said gun so that it will move with said gun in all of its aiming movements; and means for supporting said eye piece on said gun mount in a position convenient to the eye of the gunner occupying said gunner's seat and in fixed spacial relation to the gunner's seat whereby said gun mount, said gunner's seat, and said eye piece will swing as a unit.

6. A device as described in claim 5 wherein said gun mount projects through the wall of an aircraft cabin and sealing means is placed operatively around said gun mount above said eye piece of said gun sight.

7. The combination with a gun pivotally supported on a gun mount so as to swing relatively to said gun mount on one axis, and bearing means supporting said gun mount so that it will rotate on a second axis of a gun sight comprising: an upper tubular section rigidly connected to said gun so as to swing with said gun in all of its aiming movements; a lower tubular section connected to said gun mount and extending through said bearing means; means operatively connecting the lower end of said upper section with the upper end of said lower section; a gun sight optical system carried in said tubular members having its objective at the upper end of said upper tubular member and its eye piece at the lower end of said lower tubular member below said bearing means, said optical system comprising a rotating lens in said upper tubular member; and means operative in response to the swinging of said gun relatively to said gun mount to operate said rotating lens.

WOLFGANG B. KLEMPERER.
GEORGE THARRATT.
